(57) CLAIM

The ornamental design for a tag slot, as shown and described.

DESCRIPTION

FIG. 1 is perspective view a horticultural container that includes a tag slot showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged portion of the perspective view of FIG. 1 showing the area of the horticultural container having the tag slot;

FIG. 9 is an enlarged portion of the front view of FIG. 2 showing the area of the horticultural container having the tag slot;

FIG. 10 is an enlarged portion of the left side view of FIG. 4 showing the area of the horticultural container having the tag slot, a right side view of the enlarged portion of the left side view being a mirror image thereof; and, FIG. 11 is an enlarged portion of the top view of FIG. 6 showing the area of the horticultural container having the tag slot.

The broken lines shown herein are purpose of illustrating portions of the horticultural container and form no part of the claimed design.

The dash-dot broken lines represent an unclaimed boundary and form no part of the claimed design.
